LE ROY W. KELSBY

CARTRIDGE FUSE

Filed July 5, 1924

FIG. 1.

FIG. 2.

Inventor:
Le Roy W Kelsay
by *Swadams. Atty.*

UNITED STATES PATENT OFFICE.

LE ROY W. KEL SAY, OF NEW YORK, N. Y., ASSIGNOR TO WESTERN ELECTRIC COMPANY, INCORPORATED, OF NEW YORK, N. Y., A CORPORATION OF NEW YORK.

CARTRIDGE FUSE.

Application filed July 5, 1924. Serial No. 724,372.

My invention relates to fuses and particularly to fuses of the cartridge type.

The object of my invention is to provide a fuse of the type indicated which may be cheaply manufactured and which shall be efficient in operation.

Heretofore, it has been the practice to secure the end plugs to the cylindrical casing by screws, rivets, cement, or by spinning a ferrule into a groove in the casing. These methods necessarily weaken the structure of the fuse and involve expensive manufacturing operations. Again, the shrinking and swelling of the fibre tube, due to excessive dryness or moisture, causes an insecure condition in the types of construction mentioned.

In accordance with this invention, tapered end plugs, the inner ends of which are made of substantially the same diameter as the inside of the tube, are forced into the ends of the insulating tube under pressure and securely fixed in position by metal ferrules spun against the outside of the tube. The plugs are preferably provided with fins or ribs to prevent relative turning of the shell and plugs. This arrangement provides a rigid and durable construction wherein the end plugs will not be blown off by the pressure of the gas generated when the fuses are blown, and will not become loose as the fibre expands or contracts, due to atmospheric conditions.

Referring to the drawing Fig. 1 shows a fuse of this invention in partial longitudinal section, 1 indicates one of the end plugs, preferably of brass, the face of which has been knurled or ribbed as at 2, to prevent the plug from turning in the shell 8, and 3 designates the metal ferrule, the initial position of which before the spinning operation being indicated by the dot and dash outline 4. Numeral 5 designates the threaded shank which with the nut 6 and washer 7 constitute the binding post. Fig. 2 is a cross-sectional view of Fig. 1 taken at line 2-2.

In assembling the fuse, the fusible link 10 is fastened into one of the end plugs,

preferably by soldering, and the fibre insulating cylinder 8 is forced over this frusto-conical plug under pressure. The inner diameter of the plug, being of substantially the same diameter as the inside of the tube, causes the end of the tube to expand as shown by numeral 9. Then the other end 55 plug is slipped over the fuse wire 10 and forced into the other end of the tube as shown at 9. To complete the process, ferrules 3 are spun over the expanded ends of the fibre tube, thus locking the assembly, 60 and the fuse wire is soldered into place at 11.

While I have shown the preferred embodiment of my invention, changes may be effected therein without departing from the 65 spirit or scope thereof, as set forth in the appended claims.

What is claimed is:

1. In an electrical cartridge fuse, a hollow cylindrical casing, a fusible link, frusto-conical contact plugs in the ends of said casing and supporting said fusible link, said plugs being cone-shaped and their largest diameter being greater than the inside diameter of said casing and having external 70 longitudinal ribs to engage the inside of said casing, and cup-shaped ferrules secured over the distorted ends of said casing and including said plugs.

2. The method of making cartridge fuses 80 which consists in forcing apertured tapered plugs into and expanding the ends of a hollow cylindrical tube, supporting a fusible link in said plugs, and clamping collars around the tube ends and plugs. 85

3. The method of making cartridge fuses which consists in forcing longitudinally ribbed frusto-conical end plugs into the ends of a hollow cylindrical fibre tube, the largest diameter of said plugs being greater 90 than the inside diameter of said tube, and spinning metal caps over the expanded ends of said tube.

In witness whereof, I hereunto subscribe my name this 2 day of July, A. D. 1924.

LE ROY W. KEL SAY.
